(**) Term: **14 Years**

(57) **CLAIM**

(21) Appl. No.: **29/344,208**

The ornamental design for a hinge, as shown and described.

(22) Filed: **Sep. 25, 2009**

DESCRIPTION

(51) **LOC (9) Cl.** **08-06**

FIG. 1 is a perspective view of a hinge according to the invention, the hinge shown in a closed position.

(52) **U.S. Cl.** **D8/323; D11/87**

FIG. 2 is a perspective view of the hinge of FIG. 1, the hinge shown in an open position.

(58) **Field of Classification Search** D8/387,

FIG. 3 is a side view of the hinge shown in FIG. 1, the opposite side view being a mirror image thereof.

D8/323, 325, 330, 336, 349, 328, 327, 331,

FIG. 4 is a side view of the hinge shown FIG. 2, the opposite side view being a mirror image thereof.

D8/353, 338; D3/324; D11/86-89; D16/334;

FIG. 5 is a top view of the hinge shown in FIG. 1.

4/236, 240; 16/309, 235, 275, 244, 379,

FIG. 6 is a top view of the hinge shown in FIG. 2.

16/390, 430, 241, 238, 245, 236, 243, 242,

FIG. 7 is a bottom view of the hinge shown in FIG. 1.

16/385, 225, 250, 248, 381; 49/381; D23/303,

FIG. 8 is a bottom view of the hinge shown in FIG. 2.

D23/302; D10/69, 65, 61, 46; 33/347, 365-390

FIG. 9 is a front view of the hinge shown in FIG. 1.

See application file for complete search history.

FIG. 10 is a front view of the hinge shown in FIG. 2.

(56) **References Cited**

FIG. 11 is a back view of the hinge shown in FIG. 1; and,
